Burnally Axle,

Horse Power.

Patented June 13, 1832.

Thomas D. Burrall & Ichiel F. Atwell of Geneva,
of Ontario and State of New York
Letters Patent

The schedule referred to in these Letters Patent and making part
of the same, containing a description in the words of the said
Tho. D. Burrall and Ichiel F. Atwell themselves, of their im-
provement in the machine for propelling Threshing Machines
and other Machinery by horses or other animal power.

Be it known, that We, Thos. D. Burrall & Ichiel F. Atwell
of Geneva in the county of Ontario and State of New York have in-
vented a new and useful improvement in the machine for propel-
ling Threshing Machines and other machinery by horses or other
animal power; and that the following is a full & exact description
of the construction & operation of the machine for that purpose
as invented or improved by us. "Civ."

It consists of a frame, composed of two cross sills of plank
14 inch wide 3 $\frac{1}{2}$ inch thick & four feet long, placed parallel to
each other and about 6 feet apart: on the top of these is laid a
plank of similar dimensions about 8 feet long and set into the
cross sills by slight gains, on each end of this plank is raised a
head block 14 inch wide 6 inch thick, 3 $\frac{1}{2}$ inch high, resting on
the tops of these blocks is another plank of similar dimensions
of the bottom one, also set on to the head blocks by gains. Thro'
each of the head blocks are passed (perpendicularly) 2 strong
iron bolts with nuts and screws confining the top of the frame
to the cross sills, and thus binding the whole frame firmly together
without tenons or mortise.

In this frame is placed a horizontal cogwheel 3 $\frac{1}{2}$ feet
diameter the foot of the shaft of which is strapped into the bot-
tom pine of the frame. The upper end of the shaft passes thro' the
top pine of the frame by a nut & collar and on the head of the
shaft is secured a nut iron cap or trough fitted to receive a

sway or bar 10 feet long, to which the horse or other power is to be attached so as to travel around the machine in order to propel it. This lever is to be secured to the cap or trough by overbolts or bands.

At a suitable distance, in the front, from this wheel is placed a second cog-wheel of similar dimensions to the first with a pinion containing twenty teeth, more or less, upon its shaft, meshing into the teeth of the first wheel. At a suitable distance from this second wheel and as near as may be to the bottom of the front is placed a band-wheel of the same dimensions to the shaft of which is also attached a pinion, containing 12 teeth more or less, meshing into the teeth of the second wheel, thus giving a highly accelerated motion to the band-wheel. — On the side of the head block over the band-wheel is affixed a pulley over which the band passes in such a manner as to bring it nearly around the wheel before it leaves it, and thus bringing the returning part of it within a few inches of the line of draft of the other part of it. Both parts then pass horizontally in parallel lines thro' a box or trough placed upon the ground, on which the horses walk. At the other end of this box (which may be about 6 feet long) are placed 2 pulleys under which the two parts of the band pass, by which means, the line of motion is changed into any direction required. When applied to the thrashing Machine, the wheel of the cylinder of the thrashing Machine is placed directly over the pulleys, so that the band shall pass upwards from one of the pulleys to the wheel and downwards from the wheel to the other pulley, thus connecting the movements of the horse power machine, with the Thrashing Machine without the necessity of any additional fixtures or framework to set it up, so that the process of thrashing may be commenced at once by means of it, in the field or the road without tools or expense.

In this Machine, we claim the mode of connecting the power with the machinery to be propelled by means of the head-block, band-wheel and band under the horses feet, whether the band be gathered into the box or trough described by means of the pulley.

or passed under foot by two hands or otherwise - - And we also
claim the peculiarly simple, strong and useful construction &
combination of the frame of the horse power Machine, as described
above - - In Testimony whereof that the above is a true speci-
fication of our said improvement as above described we have here-
unto set our hands and seals this 20.th day of March 1832.
